ELECTROOPTIC DEVICE, DRIVING CIRCUIT, AND ELECTRONIC DEVICE

BACKGROUND

1. Technical Field

The present invention relates to a technique for electrooptic devices such as liquid crystal devices to reduce the voltage amplitude of the data lines and to achieve high-definition display.

2. Related Art

Electrooptic devices such as liquid crystal devices have pixel capacitors (liquid-crystal capacitors) corresponding to the intersections of scanning lines and data lines. When there is a need to drive the pixel capacitors by an alternating current, the components of a data-line driving circuit which provides data signals to the data lines are required to have resistance to voltage corresponding to the voltage amplitude of the data signals, because the voltage amplitude has positive and negative polarities. To meet this need, there is proposed a technique for reducing the voltage amplitude of the data signals by providing storage capacitors in parallel to the pixel capacitors and by driving capacitor lines connected to a common storage capacitor in synchronism with the selection of a scanning line in binary (refer to JP-A-2001-83943).

However, since this technique employs a structure in which a capacitor-line driving circuit and a scanning-line driving circuit (substantially, a shift register) share the same lines, the circuit configuration for driving the capacitor lines are complicated.

SUMMARY

An advantage of some aspects of the invention is to provide an electrooptic device, a driving circuit thereof, and an electronic device which can achieve high-definition display while partly reducing the voltage amplitude of the data lines with a simple circuit configuration.

According to a first aspect of the invention, there is provided a driving circuit of an electrooptic device, comprising: a plurality of scanning lines; a plurality of data lines; first and second capacitor lines corresponding to each of the plurality of scanning lines; a common electrode; pixels corresponding to the intersections of the plurality of scanning lines and the plurality of data lines, the pixels each including: a pixel switching element connected at one end to a data line corresponding to the element itself, and brought into conduction when a scanning line corresponding to the element itself is selected; a pixel capacitor disposed between the pixel switching element and the common electrode; and a storage capacitor disposed between one end of the pixel capacitor and one of the first and second capacitor lines corresponding to the scanning line; a scanning-line driving circuit that selects the scanning lines in a predetermined order; and a capacitor-line driving circuit that shifts the voltage of a first capacitor line corresponding one scanning line to a predetermined voltage when said one scanning line is selected, and when a scanning line apart from said one scanning line by predetermined number of lines is selected, changes the predetermined voltage by a predetermined value or holds the predetermined voltage; and when said one scanning line is selected, shifts the voltage of a second capacitor line corresponding said one scanning line to the predetermined voltage, and when a scanning line apart from said one scanning line by predetermined number of lines is selected, holds the predetermined voltage or changes the predetermined voltage by the predetermined value; and a data-line driving circuit that applies a data signal

2

to pixels corresponding to a selected scanning line via a data line, the data signal having a voltage corresponding to the gray level of the pixels. Thus, the voltage amplitude of the data lines can be reduced with a simple configuration, and the voltage to be written to the pixel capacitors can be changed depending on whether the storage capacitor is connected to the first capacitor line or the second capacitor line, thus allowing high-definition display.

Preferably, in the driving circuit of an electrooptic device 10 according to an embodiment of the invention, in the pixels corresponding to the one scanning line, storage capacitors corresponding to data lines in odd-numbered columns are each disposed between one end of a pixel capacitor corresponding to the pixel itself and one of the first and second 15 capacitor lines; and storage capacitors corresponding to data lines in even-numbered columns are each disposed between one end of a pixel capacitor corresponding to the pixel itself and the other one of the first and second capacitor lines. This configuration allows dot reversing in which the written polarity of pixels is reversed alternately every row and column. In 20 this embodiment, the term, odd number and the even number, is merely a relative concept for alternately specifying the successive rows and columns.

Preferably, when the one scanning line is selected, the 25 capacitor-line driving circuit connects the first capacitor line corresponding to the one scanning line to a first feed line that feeds a first capacitance signal of the predetermined voltage, and when a scanning line apart from the one scanning line by predetermined number of lines is selected, the capacitor-line 30 driving circuit connects the first capacitor line to a second feed line that feeds a second capacitance signal of one of voltages higher and lower than the predetermined voltage by a predetermined value or of the predetermined voltage; and when the one scanning line is selected, the capacitor-line 35 driving circuit connects the second capacitor line corresponding to the one scanning line to the first feed line, and when a scanning line apart from the one scanning line by predetermined number of lines is selected, the capacitor-line driving circuit connects the second capacitor line to a third feed line 40 that feeds a third capacitance signal of the predetermined voltage or the other one of voltages higher and lower than the predetermined voltage by the predetermined value.

Preferably, the first capacitance signal is temporally constant at the predetermined voltage; and the voltages of the 45 second and third capacitance signals are higher or lower exclusively from each other, and are switched every time one scanning line is selected.

Preferably, the capacitor-line driving circuit comprises: first to fourth transistors corresponding to each row, wherein the gate electrodes of the first and second transistors corresponding to the first and second capacitor lines, respectively, are connected to the scanning line corresponding to the one scanning line, and the source electrodes of the first and second transistors are connected to the first feed line; the gate electrode of the third transistor is connected to a scanning line apart from the scanning line corresponding to the one capacitor line by predetermined number of lines, and the source electrode of the third transistor is connected to the second feed line; the gate electrode of the fourth transistor is connected to a scanning line apart from the scanning line corresponding to the one capacitor line by predetermined number of lines, and the source electrode of the fourth transistor is connected to the third feed line; and the drain electrodes of the first and third transistors are connected to the first capacitor line corresponding to the line, and the drain electrodes of the second and fourth transistors are connected to the second capacitor line corresponding to the line.

Preferably, the capacitor-line driving circuit brings the first and second capacitor lines corresponding to one scanning line into high impedance after the selection of a scanning line apart from the one scanning line by predetermined number of lines and following the one scanning line is completed until the one scanning line is selected again.

Preferably, the storage capacitors in the odd-numbered rows and the odd-numbered columns and in the even-numbered rows and the even-numbered columns are each disposed between one end of a pixel capacitor corresponding to the storage capacitor itself and one of the first and second capacitor lines; the storage capacitors in the odd-numbered rows and the even-numbered columns and in the even-numbered rows and the odd-numbered columns are each disposed between one end of a pixel capacitor corresponding to the storage capacitor itself and the other one of the first and second capacitor lines; the capacitor-line driving circuit connects a first capacitor line corresponding to one scanning line to a first feed line that feeds a first capacitance signal; and when the one scanning line is selected, connects a second capacitor line corresponding to one scanning line to the first feed line, and when a scanning line apart from the one scanning line by predetermined number of lines is selected, connects the second capacitor line to a second feed line that feeds a second capacitance signal; and the first capacitance signal and the second capacitance signal are switched every period of one or a plurality of frames while holding the difference voltage therebetween at the predetermined value between the case where one is at a high level and the other is at a low level and the case where one is at a low level and the other is at a high level; and the voltage of the common electrode is the same as that of the first capacitance signal.

The invention may be embodied not only as a driving circuit of an electrooptic device but also as an electrooptic device and an electronic device equipped with the electrooptic device.

BRIEF DESCRIPTION OF THE DRAWINGS

The invention will be described with reference to the accompanying drawings, wherein like numbers reference like elements.

FIG. 1 is a block diagram showing the configuration of an electrooptic device according to a first embodiment of the invention.

FIG. 2 is a diagram showing the configuration of pixels of the electrooptic device.

FIG. 3 is a diagram showing the configuration of the boundary between the display region and the capacitor-line driving circuit of the electrooptic device.

DESCRIPTION OF EXEMPLARY EMBODIMENTS

Embodiments of the invention will be described with reference to the drawings.

First Embodiment

A first embodiment of the invention will first be described. FIG. 1 is a block diagram of an electrooptic device according to a first embodiment of the invention.

As shown in the diagram, the electrooptic device, denoted 30 at 10, has a display region 100, and a control circuit 20, a scanning-line driving circuit 140, a capacitor-line driving circuit 150, and a data-line driving circuit 190 around the display region 100. The display region 100 has an array of pixels 110, in which 321 scanning lines 112 extend transversely (in the X direction) and 240 data lines extend longitudinally (in the Y direction). The pixels 110 are disposed at the intersections of the first to 320th scanning lines 112 and the first to 240th data lines 114.

Accordingly, in this embodiment, the pixels 110 are 40 arrayed in a 320 by 240 matrix in the display region 100. The invention is not however limited to that matrix.

In this embodiment, the 321st scanning line 112 does not contribute to the vertical scanning of the display region 100 (sequential selection of scanning lines for writing voltage to 45 the pixels 110). In this embodiment, a pair of first and second capacitor lines 131 and 132 extends in the X direction such that it corresponds to the first to 320th scanning lines 112.

The pixels 110 of odd-numbered (first to 239th) columns correspond to the first capacitor line 131, while the pixels 110 of even-numbered (second to 240th) columns correspond to the second capacitor line 132. The detailed structure of the pixels 110 will now be described.

FIG. 2 shows the structure of the pixels 110, in which 2×2=4 pixels corresponding to the intersections of the ith row 55 and the adjacent (i+1)th row and the jth column and the adjacent (i+1)th column are shown.

In this embodiment, symbols i and (i+1) denote any continuous two rows of pixels 110, which range from 1 to 320. Here, symbols i and (i+1) of the rows corresponding to the 50 scanning lines 112 are integers from 1 to 321 because the dummy 321st line must be included.

On the other hand, symbol j denotes any odd-numbered column of the pixels 110, which ranges from 1 to 239. Therefore, (j+1) is an even number ranging from 2 to 240 which is 60 larger than the odd number j by one.

As shown in FIG. 2, each pixel 110 includes an n-channel thin film transistor (hereinafter, simply referred to as a TFT)

116 serving as a pixel switching element, a pixel capacitor (liquid-crystal capacitor) **120**, and a storage capacitor **130**. Since the pixels **110** have the same structure except the line to which the storage capacitor **130** is connected, the pixel **110** in the *ith* row and the *jth* column will be described as a typical example. In the pixel **110** of the *ith* row and the *jth* column, the gate electrode of the TFT **116** is connected to the *ith* scanning line **112**, the source electrode is connected to the data line **114** on the *jth* column, and the drain electrode is connected to a pixel electrode **118** which is a first end of the pixel capacitor **120**.

A second end of the pixel capacitor **120** is a common electrode **108**. The common electrode **108** is common to all the pixels **110**, to which a common signal *Vcom* is provided, as shown in FIG. 1. The common signal *Vcom* of this embodiment is a temporally constant voltage *LCcom*, as will be described later.

The storage capacitor **130** of the pixel **110** in the *ith* row and the odd-numbered *jth* column is connected to the pixel electrode **118** (the drain electrode of the TFT **116**) at one end and connected to the first capacitor line **131** in the *ith* row at the other end. The storage capacitor **130** of the pixel **110** in the *ith* row and the even-numbered (*j+1*)th column is connected to the pixel electrode **118** at one end, as that of the odd-numbered column, but is connected to the second capacitor line **132** of the *ith* row at the other end. The capacitances of the storage capacitors **130** of the odd-numbered column and the even-numbered column are equal, which are expressed as *C_s*. The capacitance of the pixel capacitor **120** is expressed as *C_{pix}*.

In FIG. 2, symbols *Y_i* and *Y_(i+1)* indicate scanning signals provided to the *ith* and (*i+1*)th scanning lines **112**, respectively, and symbols *C_{a-i}* and *C_{b-i}* indicate voltages of the first capacitor line **131** and the second capacitor line **132** corresponding to the *ith* row, respectively.

The display region **100** has a structure in which a pair of substrates, a device substrate having the pixel electrodes **118** and an opposing substrate having the common electrodes **108**, are bonded together such that the electrode formed surfaces face with a space therebetween, in which liquid crystal **105** is sealed. Thus, the pixel capacitor **120** sandwiches the liquid crystal **105** which is a kind of dielectric with the pixel electrode **118** and the common electrode **108** and holds the difference voltage between the pixel electrode **118** and the common electrode **108**. With this structure, the amount of light transmission of the pixel capacitor **120** changes with the effective value of the held voltage. It is assumed that this embodiment is in a normally white mode in which if the effective voltage held by the pixel capacitor **120** is close to zero, the light transmittance becomes the maximum to provide white display, and the amount of transmission decreases as the effective voltage increases, and it finally becomes the minimum to display in black.

Returning back to FIG. 1, the control circuit **20** outputs various control signals to control the components of the electrooptic device **10**, and provides a first capacitance signal *Vc1* to a first feed line **181**, a second capacitance signal *Vc2a* to a second feed line **182**, and a third capacitance signal *Vc2b* to a third feed line **183**, respectively. The control circuit **20** provides the common signal *Vcom* to the common electrode **108**.

Around the display region **100** are provided peripheral circuits such as the scanning-line driving circuit **140**, the capacitor-line driving circuit **150**, and the data-line driving circuit **190**. Among them, the scanning-line driving circuit **140** provides scanning signals *Y₁* to *Y₃₂₁* to the first to 321st scanning lines **112**, respectively, for the period of one frame. Specifically, the scanning-line driving circuit **140** selects the

scanning lines in the order from the first to 321st row, and provides a scanning signal of a high level corresponding to selected voltage *Vdd* to a selected scanning line, and a scanning signal of a low level corresponding to unselected voltage (ground potential *Gnd*) to the other scanning lines.

More specifically, as shown in FIG. 4, the scanning-line driving circuit **140** outputs the scanning signals *Y₁* to *Y₃₂₁* by shifting a start pulse *Dy* applied from the control circuit **20** according to a clock signal *Cly*.

As shown in FIG. 4, the period of one frame in this embodiment includes an effective scanning period *Fa* after the scanning signal *Y₁* has reached a high level until the scanning signal *Y₃₂₀* reaches a low level and the other period, that is, the flyback time after the dummy scanning signal *Y₃₂₁* has reached a high level until the scanning signal *Y₁* goes to a high level again. The period during which one scanning line **112** is selected is a horizontal scanning period *H*.

The capacitor-line driving circuit **150** of this embodiment includes a set of TFTs **51** to **54** provided for each row. The TFTs **51** to **54** corresponding to the *ith* row will be described herein. The gate electrode of the TFT **51** (a first transistor) and the gate electrode of the TFT **52** (a second transistor) are connected to the *SEith* scanning line **112** in common, and their source electrodes are connected to the first feed line **181** in common. The gate electrode of the TFT **53** (a third transistor) and the gate electrode of the TFT **54** (a fourth transistor) corresponding to the *ith* row are connected, in common, to the (*i+1*)th scanning line **112** that is selected next to the *ith* row, while the source electrode of the TFT **53** is connected to the second feed line **182**, and the source electrode of the TFT **54** is connected to the third feed line **183**. The common drain electrode of the TFTs **51** and **53** corresponding to the *ith* row is connected to the first capacitor line **131** of the *ith* row, and the common drain electrode of the TFTs **52** and **54** corresponding to the *ith* row is connected to the second capacitor line **132** of the *ith* row. While we have described the TFTs **51** to **54** of the *ith* row as a representative example, those of the other rows have the same structure.

The data-line driving circuit **190** provides data signals *X₁* to *X₂₄₀* of the voltage corresponding to the gray level of the pixels **110** on the scanning line **112** selected by the scanning-line driving circuit **140** and responsive to a polarity indication signal *Pol* to the first to 240th data lines **114**, respectively.

The data-line driving circuit **190** has storage regions (not shown) corresponding to the 320- by 240-pixel matrix array, in each of which display data *Da* that indicates the gray level (luminosity) of a corresponding pixel **110** is stored. When the display content is changed, the display data *Da* stored in each storage region is updated to new display data *Da* given along with its address by the control circuit **20**.

The data-line driving circuit **190** executes the operation of reading the display data *Da* of the pixels **110** on the selected scanning line **112** from the storage region, converting it to a data signal of a voltage corresponding to the gray level and the designated polarity, and supplying it to the data line **114**, for each of the first to 240th columns of the selected scanning line **112**.

The polarity indication signal *Pol* of this embodiment indicates, for a high level, positive writing to the pixels in the odd-numbered rows and odd-numbered columns (and in the even-numbered rows and even-numbered columns), and indicates negative writing to the pixels in the odd-numbered rows and even-numbered columns (and in the even-numbered rows and odd-numbered columns); in contrast, for a low level, the polarity indication signal *Pol* indicates negative writing to the pixels in the odd-numbered rows and odd-numbered columns (and in the even-numbered rows and even-numbered col-

ums), and positive writing to the pixels in the odd-numbered rows and even-numbered columns (and in the even-numbered rows and odd-numbered columns), thus reversing the polarity every horizontal scanning period H of one frame, as shown in FIG. 4. That is, this embodiment adopts dot reversing in which the written polarity is reversed every row and column.

The polarity indication signal Pol of adjacent frames is reversed in logic during a horizontal scanning period during which the same scanning line is selected, that is, it shifts in phase by 180 degrees during the period of the adjacent frames. The reason for reversing the polarity is to prevent the degradation of the liquid crystal due to application of a direct current component.

In this embodiment, if the voltage written to the pixel capacitor 120 corresponding to the gray level is higher than that of the common electrode 108, the polarity of the voltage is referred to as positive polarity, and if the voltage is lower, its polarity is referred to as negative polarity. The voltage is based on the ground potential Gnd of the power source, except as otherwise noted.

The control circuit 20 provides a latch pulse Lp to the data-line driving circuit 190 at the timing at which the logic level of the clock signal Cly shifts. Since the scanning-line driving circuit 140 outputs the scanning signals Y1 to Y321 by shifting the start pulse Dy in response to the clock signal Cly or the like, as described above, the timing to start the period during which a scanning line is selected is the timing at which the logic level of the clock signal Cly shifts. Thus, the data-line driving circuit 190 can be notified of a scanning line selected by continuously counting the latch pulse Lp for the period of one frame and of the scanning-line selection start timing by the timing at which the latch pulse Lp is provided.

In this embodiment, the device substrate has, in addition to the scanning lines 112, the data lines 114, the first capacitor lines 131, the second capacitor lines 132, the TFTs 116, the pixel electrodes 118, and the storage capacitors 130 in the display region 100, the TFTs 51 to 54, the first feed line 181, the second feed line 182, and the third feed line 183 of the capacitor-line driving circuit 150.

FIG. 3 is a plan view of the configuration around the boundary between the capacitor-line driving circuit 150 and the display region 100.

As shown in this drawing, the TFTs 116 and 51 to 54 are of an amorphous silicon type and of a bottom gate type in which their gate electrodes are located lower than the semiconductor layer (on the back of the drawing).

More specifically, a gate electrode layer serving as a first conductive layer is patterned into the scanning lines 112, the first capacitor lines 131, the second capacitor lines 132, and the gate electrodes of the TFTs, on which a gate insulator film (not shown) is formed, and the semiconductor layer of the TFTs is formed like islands. The semiconductor layer has thereon the rectangular pixel electrodes 118 formed by patterning an indium tin oxide (ITO) layer serving as a second conductive layer, with a protective layer therebetween. The semiconductor layer further has various connecting lines including the source electrodes and the drain electrodes of the TFTs, the data lines 114, the first feed lines 181, the second feed lines 182, and the third feed lines 183 which are formed by patterning a metal layer made of aluminum or the like serving as a third conductive layer.

The scanning lines 112 extend in the X direction in the display region 100, as described above.

The ith scanning line 112 has in the capacitor-line driving circuit 150 a branch extending in the Y direction (downward) so as to form the gate electrode of the TFTs 51 and 52, and an upward branch so as to form the gate electrode of the TFTs 53

and 54 corresponding to the (i-1)th row one row above, with the other portion extending in the X direction as in the display region 100.

The common drain electrode 62 of the TFTs 51 and 53 is formed by patterning the third conductive layer, and is connected to a line 64 formed by patterning the gate electrode layer through a contact hole (indicated by x in the drawing) in the protective layer and the gate insulating layer. The line 64 is connected to a line 66 formed by patterning the third conductive layer through a contact hole. The line 66 is connected to the first capacitor line 131 of the ith row through a contact hole.

The common drain electrode 72 of the TFT 52, and 54 is formed by patterning the third conductive layer, and is connected to the second capacitor line 132 of the ith row through a contact hole.

The third feed line 183 is connected to a line 74 formed by patterning the gate electrode layer through a contact hole. The line 74 is connected to the source electrode 76 of the TFT 54 through a contact hole. The source electrode 76 is formed by patterning the third conductive layer.

The portion (wide portion) of the first feed line 181 overlapping with the semiconductor layer of the TFTs serves as the source electrode of the TFTs 51 and 52, and the portion of the second feed line 182 overlapping with the semiconductor layer serves as the source electrode of the TFT 53.

The storage capacitors 130 corresponding to the pixels on the odd-numbered columns each have the gate insulating layer serving as a dielectric under the pixel electrode 118, the gate insulating layer being sandwiched between the wide portion of the first capacitor line 131 and the pixel electrode 118. The storage capacitors 130 in the even-numbered columns each have the gate insulating layer serving as a dielectric under the pixel electrode 118, the gate insulating layer being sandwiched between the wide portion of the second capacitor line 132 and the pixel electrode 118.

The common electrodes 108 are not shown in FIG. 3 which is a plan view of the device substrate, because they are disposed on an opposing substrate.

FIG. 3 merely shows an example and the TFTs may have another structure; for example, the gate electrodes may be of a top gate type, or the TFTs may be of a polysilicon type in term of process. The elements of the capacitor-line driving circuit 150 may not be disposed in the display region 100 but IC chips may be mounted on the device substrate.

If IC chips are mounted on the device substrate, the scanning-line driving circuit 140 and the capacitor-line driving circuit 150 may be mounted as one semiconductor chip together with the data-line driving circuit 190, or alternatively, they may be separate chips. The control circuit 20 may either be disposed on a separate flexible printed circuit (FPC) board or the like or mounted on the device substrate as a semiconductor chip.

If this embodiment is not of a transmissive type but of a reflective type, the pixel electrode 118 may be a reflective conductor pattern or a separate reflective metal pattern. As a further alternative, a semitransmissive and semireflective type that is a combination of the transmissive type and the reflective type is possible.

The operation of the electrooptic device 10 according to this embodiment will be described.

The control circuit 20 reveres the polarity of the polarity indication signal Pol every horizontal scanning period H, as described above. Thus, the polarity indication signal Pol goes to a high level at the start of the period of one frame (denoted at frame n), and reverses the polarity every horizontal scanning period H, and goes to a low level at the start of the

following (n+1) frame period, and thereafter reverses the polarity every horizontal scanning period H.

In this embodiment, the control circuit 20 controls the first capacitance signal Vc1 to the same and constant voltage LCcom as that of the common electrode 108. For the second capacitance signal Vc2a, the control circuit 20 controls it to a voltage Vs1 lower than voltage LCcom by a voltage ΔV to bring the polarity indication signal Pol to a high level, and to voltage LCcom to bring the polarity indication signal Pol to a low level. The control circuit 20 controls the third capacitance signal Vc2b to voltage LCcom to bring the polarity indication signal Pol to a high level, and to voltage Vs1 to bring the polarity indication signal Pol to a low level.

That is, the second capacitance signal Vc2a and the third capacitance signal Vc2b are switched between the voltages LCcom and Vs1 exclusively in accordance with the level of the polarity indication signal Pol every horizontal scanning period H.

For frame n, since the first scanning line 112 is first selected by the scanning-line driving circuit 140, the scanning signal Y1 goes to a high level.

When a latch pulse Lp is output at the timing that the scanning signal Y1 goes to a high level, the data-line driving circuit 190 reads the display data Da of the pixels in the first row and the first to 240th columns, and since the polarity indication signal Pol is at a high level, the data-line driving circuit 190 converts the voltage of the odd-numbered columns to a voltage higher than voltage LCcom by the voltage designated by the display data Da of the read columns, and converts the voltage of the even-numbered columns to a voltage corresponding to the display data Da of the read columns and negative polarity (its meaning will be described later).

The data-line driving circuit 190 provides the voltage converted for each column to the data lines 114 of the first to 240 columns as data signals X1 to X240.

When the scanning signal Y1 goes to a high level, the TFTs 116 of the pixels from the first row and the first column to the first row and the 240th column are turned on, so that the data signals X1 to X240 are applied to the pixel electrodes 118. Therefore, the difference voltage between the data signals X1 to X240 and voltage LCcom is written to the pixel capacitors 120 from the first row and the first column to the first row and the 240th column.

When the scanning signal Y1 goes to a high level, the TFTs 51 and 52 in the first row are turned on (the TFTs 53 and 54 are turned off) in the capacitor-line driving circuit 150. Thus, the first capacitor line 131 and the second capacitor line 132 corresponding to the first row are connected to the first feed line 181 to which the first capacitance signal Vc1 of voltage LCcom is provided.

Accordingly, the first capacitor line 131 and the second capacitor line 132 corresponding to the first row also have voltage LCcom. Thus, the difference voltage between the data signals X1 to X240 and voltage LCcom is written to the storage capacitors 130 from the first row and the first column to the first row and the 240th column in a manner similar to the pixel capacitors 120.

Then, the scanning signal Y1 goes to a low level, and the scanning signal Y2 goes to a high level.

In the capacitor-line driving circuit 150, as the scanning signal Y1 goes to a low level, the TFTs 51 and 52 in the first row are turned off, and as the scanning signal Y2 goes to a high level, the TFTs 53 and 54 in the first row are turned on. Thus, the first capacitor line 131 corresponding to the first row is connected to the second feed line 182 to which the second capacitance signal Vc2a is provided, and the second capacitor

line 132 corresponding to the first row is connected to the third feed line 183 to which the third capacitance signal Vc2b is provided.

When the scanning signal Y2 goes to a high level in frame n, the polarity indication signal Pol is inverted to a low level, so that the second capacitance signal Vc2a becomes voltage LCcom and the third capacitance signal Vc2b becomes voltage Vs1. Thus, the first capacitor line 131 corresponding to the first row is kept at voltage LCcom, but the voltage of the second capacitor line 132 corresponding to the first row shifts to voltage Vs1, dropping by a voltage ΔV .

Accordingly, when the scanning signal Y2 goes to a high level in frame n, the pixels in the first row and the odd-numbered columns hold the difference voltages that are written to the pixel capacitor 120 and the storage capacitor 130 when the scanning signal Y1 goes to a high level; for the pixels on the odd-numbered columns, with the pixel capacitor 120 and the storage capacitor 130 connected in series, the second capacitor line 132 which is the second end of the storage capacitor 130 drops by voltage ΔV while the common electrode 108 which is the second end of the pixel capacitor 120 is held constant at voltage LCcom. Thus, the difference voltages that were written to the pixel capacitor 120 and the storage capacitor 130 change when the scanning signal Y1 went to a high level. The change in the voltages will be described later.

When the latch pulse Lp is output at the timing that the scanning signal Y2 goes to a high level, the data-line driving circuit 190 reads the display data Da of the pixels in the second row and the first to 240th columns, and since the polarity indication signal Pol is reversed to a low level, the data-line driving circuit 190 converts the voltage for the odd-numbered columns to a voltage corresponding to the display data Da of the read columns and corresponding to negative polarity, and converts the voltage for the even-numbered columns to a voltage higher than voltage LCcom by the voltage corresponding to the display data Da of the read columns, and applies the voltages converted for the columns to the data lines 114 on the first to 240th columns as data signals X1 to X240.

When the scanning signal Y2 is at a high level, the TFTs 116 of the pixels from the second row and the first column to the second row and the 240th column are turned on. Thus, the difference voltage between the data signals X1 to X240 and voltage LCcom is written to the pixel capacitors 120 from the second row and the first column to the second row and the 240th column.

In addition, for the capacitor-line driving circuit 150, when the scanning signal Y2 is at a high level, the TFTs 51 and 52 in the second row are turned on. Thus, the first capacitor line 131 and the second capacitor line 132 corresponding to the second row are connected to the first feed line 181 to carry voltage LCcom.

Accordingly, the difference voltage between the data signals X1 to X240 and voltage LCcom is written to the storage capacitors 130 from the second row and the first column to the second row and the 240th column in a manner similar to the pixel capacitor 120.

Then, the scanning signal Y2 goes to a low level, and the scanning signal Y3 goes to a high level.

In the capacitor-line driving circuit 150, since the scanning signal Y2 goes to a low level, the TFTs 53 in the first row are turned off. Therefore, the first capacitor line 131 corresponding to the first row is disconnected from any part into high impedance but is held by its parasitic capacitance at voltage LCcom just before the TFTs 53 are turned off.

11

Similarly, since the scanning signal Y2 goes to a low level, the TFT 54 in the first row is turned off. Therefore, the second capacitor line 132 corresponding to the first row goes into high impedance but is held by its parasitic capacitance at voltage Vs1 just before the TFT 54 is turned off.

Accordingly, the pixel capacitors 120 in the first row and the odd-numbered columns hold the difference voltage between the voltage of the data signal written when the scanning signal Y1 is at a high level and the voltage LCcom of the common electrode 108, while the pixel capacitors 120 in the first row and the even-numbered columns hold the voltage changed when the scanning signal Y2 goes to a high level.

The second row of the capacitor-line driving circuit 150 will be described. Since the scanning signal Y2 goes to a low level, the TFTs 51 and 52 in the second row are turned off, and since the scanning signal Y3 goes to a high level, the TFTs 53 and 54 in the second row are turned on.

When the scanning signal Y3 in frame n goes to a high level, the polarity indication signal Pol is reversed again to a high level, so that the second capacitance signal Vc2a becomes voltage Vs1 and the third capacitance signal Vc2b becomes voltage Lcom, and therefore, the voltage of the first capacitor line 131 corresponding to the second row becomes voltage Vs1, dropping by ΔV , and the second capacitor line 132 corresponding to the second row is held at voltage LCcom, with no change in voltage.

Accordingly, when the scanning signal Y3 goes to a high level in frame n, in the pixels of the second row and the odd-numbered columns, with the pixel capacitor 120 and the storage capacitor 130 connected in series, the second capacitor line 132 which is the second end of the storage capacitor 130 drops by ΔV , while the common electrode 108 which is the second end of the pixel capacitor 120 is held constant at voltage LCcom. Therefore, the difference voltage that was written to the pixel capacitor 120 and the storage capacitor 130 when the scanning signal Y2 went to a high level changes. On the other hand, in the pixels of the odd-numbered columns, the difference voltage written to the pixel capacitor 120 and the storage capacitor 130 when the scanning signal Y2 went to a high level is held.

When the scanning signal Y3 goes to a high level, the voltage writing operation similar to that when the scanning signal Y1 was at a high level is executed for the pixels from the third row and the first column to the third row and the 240th column.

Then, the scanning signal Y3 goes to a low level, and the scanning signal Y4 goes to a high level.

In the capacitor-line driving circuit 150, since the scanning signal Y3 goes to a low level, the TFT 53 in the second row is turned off, and therefore, the first capacitor line 131 corresponding to the second row goes into high impedance but is held at voltage Vs1 which is the voltage directly before the TFT 53 is turned off by its parasitic capacitance. Similarly, since the scanning signal Y3 goes to a low level, the TFT 54 in the second row is turned off, and thus, the second capacitor line 132 corresponding to the second row goes into high impedance but is held at voltage LCcom which is the voltage directly before the TFT 54 is turned off.

Accordingly, the pixel capacitors 120 in the second row and the odd-numbered columns are held at the voltage changed when the scanning signal Y2 went to a high level, while the pixel capacitors 120 in the second row and the even-numbered columns are held at the difference voltage between the voltage of the data signal written when the scanning signal Y2 was at a high level and the voltage LCcom of the common electrode 108.

12

When the scanning signal Y4 goes to a high level, the voltage writing operation similar to that when the scanning signal Y2 was at a high level is executed for the pixels from the fourth row and the first column to the fourth row and the 240th column.

The same operation is repeated in frame n.

Specifically, when a scanning line in an odd-numbered row is selected in frame n and the scanning signal to the scanning line goes to a high level, in the pixels of the preceding even-numbered row and the odd-numbered columns, the difference voltage written to the pixel capacitor 120 and the storage capacitor 130 changes; for the pixels in the even-numbered rows and the even-numbered columns, the difference voltage written to the pixel capacitor 120 and the storage capacitor 130 is held; for the pixels in the odd-numbered rows and the odd-numbered columns, the difference voltage between the voltage higher than voltage LCcom by the voltage designated by the read display data Da and voltage LCcom is written to the pixel capacitor 120 and the storage capacitor 130; and for the pixels in the odd-numbered rows and the even-numbered columns, the difference voltage between the voltage corresponding to the read display data Da and to the negative polarity and voltage LCcom is written to the pixel capacitor 120 and the storage capacitor 130.

When a scanning line in an even-numbered row is selected in frame n and the scanning signal to the scanning line goes to a high level, for the pixels in the preceding odd-numbered row and the odd-numbered columns, the difference voltage written to the pixel capacitor 120 and the storage capacitor 130 is held, and for the pixels in the odd-numbered rows and the even-numbered columns, the difference voltage written to the pixel capacitor 120 and the storage capacitor 130 changes and; for the pixels in the even-numbered rows and the odd-numbered columns, the difference voltage between the voltage corresponding to the read display data Da and to the negative polarity and voltage LCcom is written to the pixel capacitor 120 and the storage capacitor 130, and for the pixels in the even-numbered rows and the even-numbered columns, the difference voltage between the voltage higher than voltage LCcom by the voltage designated by the read display data Da and voltage LCcom is written to the pixel capacitor 120 and the storage capacitor 130.

Since no pixel is present in the 321st scanning line 112, when the scanning signal Y321 goes to a high level, only the operation of turning on the TFTs 53 and 54 corresponding to the immediately preceding 320th row to connect the first capacitor line 131 in the 320th row to the second feed line 182 and connect the second capacitor line 132 to the third feed line, respectively, is executed.

In the following frame (n+1), the phase of the polarity indication signal Pol shifts by 180 degrees. Therefore, the operation of the pixels in the odd-numbered rows and odd-numbered columns (and the even-numbered rows and the even-numbered columns) in frame (n+1) are the same as that of the pixels in the odd-numbered rows and the even-numbered columns (and the even-numbered rows and the odd-numbered columns) in frame n, and the operation of the pixels in the odd-numbered rows and the even-numbered columns (and the even-numbered rows and the odd-numbered columns) in frame (n+1) are the same as that of the pixels in the odd-numbered rows and the odd-numbered columns (and the even-numbered rows and the even-numbered columns) in frame n.

The changes in the voltages of the pixel capacitors 120 between the odd-numbered rows and the even-numbered columns (and the even-numbered rows and the odd-numbered columns) in frame n and in the odd-numbered rows and

the odd-numbered columns (and the even-numbered rows and the even-numbered columns) will be described.

FIGS. 7A and 7B show the operation of holding the voltage of the pixel capacitors 120 of the pixels in the odd i^{th} row and the odd j^{th} column and the adjacent pixels in the odd i^{th} row and the even $(j+1)^{th}$ column.

When a scanning signal Y_i goes to a high level, TFTs 116 in the ith row and the jth column and in the ith row and the $(j+1)^{th}$ column are turned on as shown in FIG. 7A. Therefore, for the pixel in the ith row and the jth column, a data signal X_j is applied to a first end of the pixel capacitor 120 (the pixel electrode 118) and to a first end of the storage capacitor 130, and for the pixel in the ith row and the $(j+1)^{th}$ column, a data signal $X_{(j+1)}$ is applied to a first end of the pixel capacitor 120 and to a first end of the storage capacitor 130.

When the scanning signal Y_i is at a high level, the TFTs 51 and 52 corresponding to the ith row are turned on in the capacitor-line driving circuit 150. Therefore, both the voltage Ca_i of the first capacitor line 131 and the voltage Cb_i of the second capacitor line 132 shifts to voltage $Lcom$, as described above.

The pixel in the ith row and the jth column in frame n does not change in the written positive voltage. Therefore, the pixel in the odd i^{th} row and the even $(j+1)^{th}$ column will be described. The pixel capacitor 120 and the storage capacitor 130 in the ith row and the even $(j+1)^{th}$ column are charged with a voltage $(Vb - Lcom)$, where Vb is the voltage of the data signal $X_{(j+1)}$.

When the scanning signal Y_i goes to a low level, the TFTs 116 in the ith row and the jth column and in the ith row and the $(j+1)^{th}$ column are turned off, as shown in FIG. 7B. When the scanning signal Y_i goes to a low level, the following scanning signal $Y_{(i+1)}$ goes to a high level (the $(i+1)^{th}$ row is not shown in FIG. 7B). Therefore, the TFTs 53 and 54 corresponding to the ith row are turned on in the capacitor-line driving circuit 150. Thus, the voltage Ca_i of the first capacitor line 131 of the ith row to which the second end of the storage capacitor 130 in the odd j^{th} column is connected shifts to the voltage $Lcom$ of the second capacitance signal $Vc2a$ applied to the second feed line 182, which is not changed from that when the scanning signal Y_i was at a high level. In contrast, the voltage Cb_i of the second capacitor line 132 of the ith row to which the second end of the storage capacitor 130 is connected shifts to the voltage $Vs1$ of the third capacitance signal $Vc2b$ applied to the third feed line 183, which drops by ΔV from that when the scanning signal Y_i was at a high level.

Since the common electrode 108 is constant at voltage $Lcom$, the electric charge stored in the pixel capacitor 120 in the ith row and the $(j+1)^{th}$ column moves to the storage capacitor 130, decreasing the voltage of the pixel electrode 118.

Specifically, since the voltage of the second end of the storage capacitor 130 drops by ΔV with the voltage of the second end (common electrode) of the pixel capacitor 120 held constant, with the pixel capacitor 120 and the storage capacitor 130 connected in series, the pixel electrode 118 also drops in voltage.

Therefore, the voltage of the pixel electrode 118 which is the point of series connection is expressed by

$$Vb - \{Cs/(Cs+Cpix)\} \cdot \Delta V,$$

which is decreased from the voltage Vb of the data signal when the scanning signal Y_i was at a high level by the value obtained by multiplying the voltage change ΔV of the second capacitor line 132 of the ith row by the capacitance ratio of the pixel capacitor 120 to the storage capacitor 130 $\{Cs/(Cs+Cpix)\}$.

In other words, when the voltage Cb_i of the second capacitor line 132 of the ith row drops by ΔV , the voltage of the pixel electrode 118 drops from the voltage Vb of the data signal when the scanning signal Y_i was at a high level by $\{Cs/(Cs+Cpix)\} \cdot \Delta V$ ($= \Delta V_{pix}$). Here, the parasitic capacitances of the components are ignored.

In frame n, the data signal $X_{(j+1)}$ when the scanning signal Y_i is at a high level is set to voltage Vb in anticipation of the voltage drop ΔV_{pix} of the pixel electrode 118. That is, the data signal $X_{(j+1)}$ is set so that the voltage of the pixel electrode 118 after the drop becomes lower than the voltage $Lcom$ of the common electrode 108 and that the difference voltage therebetween corresponds to the gray level of the ith row and $(j+1)^{th}$ column.

Specifically, as shown in FIGS. 8A and 8B, the embodiment is set in such a manner that, in frame n, first, the data signal X_j of a voltage in the range a from voltage $Vw(+)$ corresponding to white w to voltage $Vb(+)$ corresponding to black b and increasing in voltage with respect to $Lcom$ as the gray level decreases (becomes dark) is applied to the pixels in the odd j^{th} column to which positive writing is designated; and the data signal $X_{(j+1)}$ is applied to the pixels in the even $(j+1)^{th}$ columns to which negative writing is designated such that voltage $Vb(+)$ is set for white w and voltage $Vw(+)$ is set for black b, which is in the same range a as that for the positive writing and reversed in gray level; secondly, when the voltage of the data signal $X_{(j+1)}$ is written and the pixel electrode 118 drops by voltage ΔV_{pix} , the voltage ΔV ($= Lcom - Vs1$) is set so that the voltage of the pixel electrode 118 comes within the range from voltage $Vw(-)$ corresponding to the negative white to voltage $Vb(-)$ corresponding to black and is symmetrical to the positive voltage about voltage $Lcom$.

Thus, in frame n, in the pixels of the odd-numbered columns to which negative writing is designated, the voltage of the pixel electrode 118 which has dropped by ΔV_{pix} shifts to a voltage in the negative voltage range c corresponding to the gray level and decreases with respect to voltage $Lcom$ as the gray level decreases (becomes dark).

While FIGS. 7A and 7B illustrate negative writing by changing the voltage of the pixel capacitor 120 of an odd-numbered row and an even-numbered column in frame n, negative writing for the even-numbered rows is executed by changing the voltage of the pixel capacitors 120 in the odd-numbered columns. In contrast, for the odd-numbered rows and the odd-numbered columns in frame n, the voltage of the first capacitor line 131 does not change after a positive voltage is written, and for the even-numbered rows and the even-numbered columns, the voltage of the second capacitor line 132 does not change after a positive voltage is written. Accordingly, the positive writing is executed such that the written voltage is held.

For the following frame (n+1), negative writing is executed when the voltage of the pixel capacitors 120 in the odd-numbered row and the odd-numbered column and in the even-numbered row and the even-numbered column changes. For the odd-numbered rows and the even-numbered columns in frame (n+1), the voltage of the second capacitor line 132 does not change after a positive voltage is written, and for the even-numbered rows and the odd-numbered columns, the voltage of the first capacitor line 131 does not change after a positive voltage is written, and thus, the positive writing is executed such that the written voltage is held.

FIG. 5 shows the change of the voltage $\Delta V_{pix}(i, j)$ of the pixel electrode 118 in the ith row and the jth column in relation to the scanning signals Y_i and $Y_{(i+1)}$ and the voltage Ca_i of the first capacitor line 131 of the ith row, representing the

pixels in the odd-numbered rows and the odd-numbered columns. As shown in the drawing, for the pixels in the odd-numbered rows and the odd-numbered columns, positive writing without the voltage change of the first capacitor line 131 and negative writing with a decrease ΔV in the voltage of the first capacitor line 131 are executed every one frame. This also applies to the pixels in the even-numbered rows and the even-numbered columns.

FIG. 6 shows the change of the voltage $\Delta V_{pix}(i, j+1)$ of the pixel electrode 118 in the ith row and the $(j+1)^{th}$ column in relation to the scanning signals Y_i and $Y(i+1)$ and the voltage $Cb-i$ of the second capacitor line 132 of the ith row, representing the pixels in the odd-numbered rows and the even-numbered columns. As shown in the drawing, for the pixels in the odd-numbered rows and the even-numbered columns, negative writing accompanying a decrease ΔV in the voltage of the second capacitor line 132 and positive writing without the voltage change of the second capacitor line 132 are executed every one frame. This also applies to the pixels in the even-numbered rows and the odd-numbered columns.

Referring to FIG. 5, the part of the voltage $Ca-i$ shown by the broken lines indicates that the first capacitor line 131 of the ith row is in high impedance. Referring to FIG. 6, the part of the voltage $Cb-i$ shown by the broken lines indicates that the second capacitor line 132 of the ith row is in high impedance.

Thus, this embodiment adopts dot reversing in which the written polarity of pixels is reversed alternately every row and column, thus allowing high contrast ratio and high definition display with reduced flicker.

In this embodiment, the voltage range a of data signals to pixels to which negative writing is designated is the same as that of data signals to pixels to which positive writing is designated. However, the voltage of the pixel electrode 118 after the change shifts to the range c of a negative voltage corresponding to the gray level. Thus, this embodiment allows the components of the data-line driving circuit 190 not to have high resistance to voltage and decreases the voltage amplitude of the data lines 114 having parasitic capacitance, thus eliminating the waste of power by the parasitic capacitance.

Specifically, when the pixel capacitor 120 is driven by alternating current in a structure in which the common electrode 108 is held at voltage LC_{com} and one capacitor line is provided for each row, whose voltage is set constant over all the frames, and if a voltage ranging from positive voltage $Vw(+)$ to $Vb(+)$ is written to the pixel electrode 118 in accordance with the gray level in one frame, a voltage ranging from voltage $Vw(-)$ to $Vb(-)$ corresponding to the negative polarity and reversed with reference to voltage LC_{com} must be written in the next frame, if the gray level does not change. Therefore, with the common electrode 108 held constant in voltage and the capacitor line is held constant in voltage, the resistance to voltage of the components of the data-line driving circuit 190 must be provided for the range b because the voltage of the data signal ranges over the range b . Furthermore, when the voltage of the data lines 114 having parasitic capacitance changes in voltage in the range b , its power is wasted by the parasitic capacitance. This embodiment can eliminate such disadvantages.

In this embodiment, the second capacitance signal $Vc2a$ and the third capacitance signal $Vc2b$ are switched between the voltages LC_{com} and $Vs1$ every horizontal scanning period H , which are exclusive (complementary) to each other. Thus, the power wasted by the parasitic capacitance of the second feed line 182 and the third feed line 183 can be reduced.

This embodiment has a structure in which, in each row, the second ends of the storage capacitors 130 in the odd-numbered columns are connected to the first capacitor line 131 and the second ends of the storage capacitors 130 in the even-numbered columns are connected to the second capacitor line 132. Instead, as shown by the black dots in each pixel 110 in FIG. 9, in each row, the second ends of the storage capacitors 130 in the odd-numbered columns may be connected to the second capacitor line 132 and the second ends of the storage capacitors 130 in the even-numbered columns may be connected to the first capacitor line 131. FIG. 10 is a plan view of the boundary between the capacitor-line driving circuit 150 and the display region 100 of the device substrate with such an opposite configuration.

Furthermore, this embodiment uses voltage LC_{com} and voltage $Vs1$ lower than the voltage LC_{com} by ΔV as the voltages of the second capacitance signal $Vc2a$ and the third capacitance signal $Vc2b$. In place of voltage $Vs1$, a voltage higher than the voltage LC_{com} by ΔV may be used.

Referring back to FIG. 4, in the period from the completion of the selection of the 321st scanning line 112 to the start of the selection of the first scanning line 112, the second capacitance signal $Vc2a$ of the second feed line 182 and the third capacitance signal $Vc2b$ of the third feed line 183 may be held constant in voltage.

Second Embodiment

A second embodiment of the invention will be described. FIG. 11 is a block diagram of an electrooptic device according to the second embodiment; and FIG. 12 is a plan view of the boundary between the capacitor-line driving circuit 150 and the display region 100 of the device substrate.

The second embodiment is different from the first embodiment shown in FIG. 1 (FIG. 3) in the following points: the configuration of the capacitor-line driving circuit 150 (a first difference); there is no third feed line (a second difference); the relationship between the line to which the second end of the storage capacitor 130 is connected and the capacitor line (a third difference); and the common signal $Vcom$ applied to the common electrode 108 is not constant in voltage (a fourth difference).

The second embodiment will be described centering on these differences.

The first and second differences will first be described. The capacitor-line driving circuit 150 of the second embodiment has only a set of TFTs 51 and 54 for each row. The gate electrode of the TFT 51 corresponding to the ith row is connected to the ith scanning line 112, and the source electrode is connected to a first feed line 185. The gate electrode of the TFT 54 corresponding to the ith row is connected to the $(i+1)^{th}$ scanning line 112, and the source electrode is connected to a second feed line 187. The common drain electrode of the TFTs 51 and 54 corresponding to the ith row is connected to the second capacitor line 132 of the ith row. The first capacitor line 131 of the ith row is connected to the first feed line 185 without passing through the TFTs.

The third difference will next be described. In the second embodiment, as indicated by the dots in the pixels 110 in FIG. 11, the second ends of the storage capacitors 130 in the odd-numbered rows and the odd-numbered columns and in the even-numbered rows and the even-numbered columns are connected to the respective first capacitor lines 131, and the second ends of the storage capacitors 130 in the odd-numbered rows and the even-numbered columns and in the even-numbered rows and the odd-numbered columns are connected to the respective second capacitor lines 132.

The fourth difference will then be described. As shown in FIG. 13, the common signal $Vcom$ is held at a voltage $Vs1$

over frame n, and at a voltage V_{sh1} over the next frame (n+1). The control circuit 20 of the second embodiment applies a first capacitance signal V_{c1} to the first feed line 185, and a second capacitance signal V_{c2} to the second feed line 187, respectively. As shown in FIG. 13, the first capacitance signal V_{c1} agrees with the common signal V_{com} , and the second capacitance signal V_{c2} is held at a voltage V_{sl2} over frame n, and held at a voltage V_{sh2} over the next frame (n+1). The voltages V_{sl1} , V_{sl2} , V_{sh1} , and V_{sh2} have the relation of $V_{sh2} - V_{sh1} = V_{sl1} - V_{sl2} = \Delta V$.

The operation of the electrooptic device according to the second embodiment will next be described.

Since the first capacitor lines 131 are connected to the first feed line 185, the first capacitor lines 131 come to have the same voltage as the first capacitance signal V_{c1} . Therefore, the voltage C_{a-i} of the first capacitor line 131 of the ith row shifts to voltage V_{sl1} in frame n, and shifts to voltage V_{sh1} in the next frame (n+1) (see FIGS. 13 and 14).

On the other hand, the second capacitor lines 132 are each connected to the first feed line 185 when the TFT 51 is turned on as the scanning signal to the line corresponding thereto goes to a high level, and when the scanning signal for the line next to the corresponding line goes to a high level, the second capacitor lines 132 are each connected to the second feed line 187 as the TFT 54 is turned on. Thus, in frame n, the voltage C_{b-i} of the second capacitor line 132 in the ith row shifts to voltage V_{sl1} in the period during which the scanning signal Y_i goes to a high level, and shifts to voltage V_{sl2} in the period during which the scanning signal $Y_{(i+1)}$ goes to a high level, decreasing by voltage ΔV , and when the scanning signal $Y_{(i+1)}$ goes to a low level, the voltage C_{b-i} goes into high impedance. In the next frame (n+1), the voltage C_{b-i} shifts to voltage V_{sh1} in the period during which the scanning signal Y_i goes to a high level, and shifts to voltage V_{sh2} in the period during which the scanning signal $Y_{(i+1)}$ goes to a high level, increasing by voltage ΔV , and when the scanning signal $Y_{(i+1)}$ goes to a low level, the voltage C_{b-i} goes into high impedance (see FIGS. 13 and 15).

In this embodiment, the pixels in which the second ends of the storage capacitors 130 are connected to the first feed line 185 via the first capacitor lines 131 are of the odd-numbered rows and the odd-numbered columns and of the even-numbered rows and the even-numbered columns. These pixels do not change in voltage after the voltages of the data signals are written. Therefore, for the pixels in the odd-numbered rows and the odd-numbered columns and in the even-numbered rows and the even-numbered columns in frame n, data signals with a voltage higher than the voltage V_{sl1} of the common signal V_{com} by the voltage corresponding to the gray level is written; and for frame (n+1), data signals with a voltage lower than the voltage V_{sl1} of the common signal V_{com} by the voltage corresponding to the gray level is written.

On the other hand, the pixels in which the second ends of the storage capacitors 130 are connected to the second capacitor lines 132 are of the odd-numbered rows and the even-numbered columns and of the even-numbered rows and the odd-numbered columns. These pixels change in the voltage of the second capacitor lines 132 by ΔV after the voltages of the data signals are written. Therefore, for the pixels in the odd-numbered row and the even-numbered columns and in the even-numbered rows and the odd-numbered columns in frame n, when scanning lines corresponding thereto are selected, data signals of a voltage that is set in anticipation of a voltage drop ΔV_{pix} of the pixel electrodes due to the voltage drop ΔV of the second capacitor lines 132 (i.e., a voltage decreased by ΔV_{pix} becomes lower than the voltage V_{sl1} of the common signal V_{com} by a voltage corresponding to the

gray level) are written; and for frame (n+1), when scanning lines corresponding thereto are selected, data signals of a voltage that is set in anticipation of an increase ΔV_{pix} of the voltage of the pixel electrodes due to the increase ΔV of the voltage of the second capacitor lines 132 (i.e., a voltage increased by ΔV_{pix} becomes higher than the voltage V_{sl1} of the common signal V_{com} by a voltage corresponding to the gray level) are written.

In the second embodiment, the line to which the second 10 ends of the storage capacitors 130 to be connected may be changed; the second ends of the storage capacitors 130 in the odd-numbered rows and the odd-numbered columns and in the even-numbered rows and the even-numbered columns may be connected to the second capacitor lines 132, and the 15 second ends of the storage capacitors 130 in the odd-numbered rows and the even-numbered columns and in the even-numbered rows and the odd-numbered columns may be connected to the first capacitor lines 131.

In the second embodiment, the voltage of the common 20 signal V_{com} applied to the common electrode 108 changes at the first (last) of the period of one frame. Thus, for the pixels in the odd-numbered rows and the odd-numbered columns and in the even-numbered rows and the even-numbered columns, when the common electrode 108 changes in voltage, 25 the first capacitor lines 131 also change by the same amount in the same direction at the same time, and for the pixels in the odd-numbered rows and the even-numbered columns and in the even-numbered rows and the odd-numbered columns, when the common electrode 108 changes in voltage, the 30 second capacitor lines 132 are in high impedance.

Accordingly, in the second embodiment, when the common electrode 108 changes in voltage, the voltage $Pix(i, j)$ of the pixel electrode in the odd i^{th} row and the odd j^{th} column changes by the same amount in the same direction at the same 35 time, as shown in FIG. 14; and the voltage $Pix(i, j+1)$ of the pixel electrode in the odd i^{th} row and the even $(j+1)^{th}$ column changes by the same amount in the same direction at the same time, as shown in FIG. 15. Therefore, the effective voltages (hatched portions) held in the pixel capacitors 120 are not 40 influenced.

Thus, the second embodiment adopts dot reversing in which the written polarity is reversed every row and column, as in the first embodiment. Thus, the embodiment allows high contrast ratio and high definition display with reduced flicker.

45 The capacitor-line driving circuit 150 of the second embodiment has not the TFTs 52 and 53 of the first embodiment for each row. This simplifies the configuration and reduces the region of the device substrate which does not contribute to display (i.e., the frame), thus reducing the cost.

In addition, the voltages of the first capacitance signal V_{c1} (the common signal V_{com}) and the second capacitance signal V_{c2} are changed not during the horizontal scanning period H as in the first embodiment but during the period of one frame. Thus, the power consumed by the parasitic capacitor with 50 changes in voltage can be reduced.

In the foregoing embodiments, the negative writing is 55 executed by decreasing the voltage of the capacitor lines by ΔV , and the positive writing is executed by holding the voltage of the capacitor lines. Conversely, the positive writing may be executed by increasing the voltage of the capacitor lines by ΔV , and the negative writing may be executed by holding the voltage of the capacitor lines.

In the first embodiment, the gate electrodes of the TFTs 53 60 and 54 in the ith row of the capacitor-line driving circuit 150 (in the second embodiment, the gate electrode of the TFT 54) is connected to the next $(i+1)^{th}$ scanning line 112. However, it may be connected to a scanning line 112 apart therefrom by m

lines. However, as the number of m increases, the gate electrodes of the TFTs **53** and **54** (**54**) in the ith row must be connected to a $(i+m)^{th}$ scanning line **112**, thus complicating the wiring. Furthermore, this requires m dummy scanning lines **112** to turn on the TFTs **53** and **54** (**54**) corresponding to the capacitor lines of the last 320th row.

If m is 1 as in the foregoing embodiments, the flyback time may be eliminated, and the gate electrodes of the TFTs **53** and **54** (**54**) corresponding to the second capacitor line **132** of the 320th row may be connected to the scanning line **112** of the first row. If m is 2, the flyback time may also be eliminated, and the gate electrodes of the TFTs **53** and **54** (**54**) corresponding to the 319th and the 320th rows may be connected to the scanning lines **112** of the first and second rows, respectively. This eliminates the need for the dummy scanning line.

In the foregoing embodiments, since the vertical scanning is executed downward, the gate electrodes of the TFTs **53** and **54** (**54**) of the ith row are connected to the scanning line **112** of the $(i+1)^{th}$ row. For upward vertical scanning, the gate electrodes may be connected to the scanning line **112** of the $(i-1)^{th}$ row. In other words, the gate electrodes of the TFTs **53** and **54** (**54**) in the ith row may be connected to a scanning line **112** other than the ith scanning line and which is selected in the vertical scanning direction after the ith scanning line is selected.

While the pixel capacitor **120** of the foregoing embodiments has a configuration in which the liquid crystal **105** is sandwiched between the pixel electrode **118** and the common electrode **108**, and the electric field applied to the liquid crystal **105** is perpendicular to the substrate surface. Instead, the pixel electrode, the insulating layer, and the common electrode may be disposed in layers and the electric field applied to the liquid crystal may be parallel with the substrate surface.

In the foregoing embodiments, the written polarity is reversed every period of one frame in units of the pixel capacitor **120**. This is merely for driving the pixel capacitor **120** with an alternating current. Thus, the polarity may be reversed every two or more frames.

While the pixel capacitor **120** is set in a normally white mode, it may be set in a normally black mode in which pixels become dark under no voltage. Three pixels of red, green, and blue may constitute one dot for color display; four pixels including additional color (e.g., cyan) may constitute one dot to improve the color reproducibility.

In the foregoing description, the polarity writing is based on the voltage of the common electrode **108**. This is for the case where the TFTs **116** of the pixels **110** function as ideal switches. However the fact is that the parasitic capacitance between the gate electrode and the drain electrode of the TFT **116** causes a phenomenon (referred to as push-down, punch through, or field through) in which the potential of the drain electrode (the pixel electrode **118**) is decreased when the TFT **116** is turned off. The pixel capacitor **120** must be driven by alternating current to prevent degradation of the liquid crystal. However, if the pixel capacitor **120** is driven by alternating current using the voltage applied to the common electrode **108** as the reference of written polarity, the effective voltage of the pixel capacitor **120** by negative writing becomes a little higher than that by positive writing (when the TFT **116** is of an n-channel type). Therefore, in practice, the reference voltage of the polarity writing may be separated from the voltage of the common electrode **108**. More specifically, the reference voltage of the polarity writing may be shifted higher than the voltage of the common electrode to offset the influence of the push-down.

Since the storage capacitor **130** is insulated for a direct current, such conditions that the voltage of the first or second capacitor line changes by ΔV after voltage is written to the pixel capacitor **120** and the storage capacitor **130** may be met.

5 Electronic Device

An electronic device equipped with the electrooptic device **10** according to the embodiments as a display will now be described. FIG. 16 illustrates the structure of a portable phone **1200** that adopts the electrooptic device **10** according to either 10 of the embodiments.

As illustrated, the portable phone **1200** includes a plurality of operation buttons **1202**, an ear piece **1204**, a mouthpiece **1206**, and the electrooptic device **10**. The components of the electrooptic device **10** other than that corresponding to the 15 display region **100** do not appear externally.

Examples of electronic devices incorporating the electrooptic device **10** include, in addition to the portable phone shown in FIG. 16, digital still cameras, notebook computers, liquid crystal televisions, viewfinder (or monitor-direct-view 20 type) videotape recorders, car navigation systems, pagers, electronic notebooks, calculators, word processors, workstations, TV phones, POS terminals, and devices having a touch panel. Obviously, the electrooptic device **10** can be used as the displays of the various electronic devices.

The entire disclosure of Japanese Patent Application No. 2006-237366, filed Sep. 1, 2006 is expressly incorporated by reference herein.

What is claimed is:

1. A driving circuit of an electrooptic device, comprising: a plurality of scanning lines; a plurality of data lines; first and second capacitor lines corresponding to each of the plurality of scanning lines, wherein the first capacitor line is separate from the second capacitor line; a common electrode; rows and columns of pixels corresponding to the intersections of the plurality of scanning lines and the plurality of data lines, the pixels each including: a pixel switching element connected at one end to a data line corresponding to the element itself, and brought into conduction when a scanning line corresponding to the element itself is selected; a pixel capacitor disposed between the pixel switching element and the common electrode; and a storage capacitor disposed between one end of the pixel capacitor and one of the first and second capacitor lines corresponding to the scanning line; a scanning-line driving circuit that selects the scanning lines in a predetermined order; and a capacitor-line driving circuit that shifts the voltage of a first capacitor line corresponding to one scanning line to a predetermined voltage when the one scanning line is selected, and when a scanning line apart from the one scanning line by predetermined number of lines is selected, changes the predetermined voltage by a predetermined value or holds the predetermined voltage; and when the one scanning line is selected, shifts the voltage of a second capacitor line corresponding to the one scanning line to the predetermined voltage, and when a scanning line apart from the one scanning line by predetermined number of lines is selected, holds the predetermined voltage or changes the predetermined voltage by the predetermined value; and a data-line driving circuit that applies a data signal to pixels corresponding to a selected scanning line via a data line, the data signal having a voltage corresponding to the gray level of the pixels,

21

wherein a first end of the storage capacitor is connected to the pixel capacitor, and a second end of the storage capacitor is connected to only one of the first and second capacitor lines, and

wherein the first capacitor lines are connected to odd-numbered columns of pixels, and the second capacitor lines are connected to even-numbered columns of pixels;

when the one scanning line is selected, the capacitor-line driving circuit connects the first capacitor line corresponding to the one scanning line to a first feed line that feeds a first capacitance signal of the predetermined voltage, and when a scanning line apart from the one scanning line by predetermined number of lines is selected, the capacitor-line driving circuit connects the first capacitor line to a second feed line that feeds a second capacitance signal of one of voltages higher and lower than the predetermined voltage by a predetermined value or of the predetermined voltage; and

when the one scanning line is selected, the capacitor-line driving circuit connects the second capacitor line corresponding to the one scanning line to the first feed line, and when a scanning line apart from the one scanning line by predetermined number of lines is selected, the capacitor-line driving circuit connects the second capacitor line to a third feed line that feeds a third capacitance signal of the predetermined voltage or the other one of voltages higher and lower than the predetermined voltage by the predetermined value;

the capacitor-line driving circuit comprises:

first to fourth transistors corresponding to each row, wherein

the gate electrodes of the first and second transistors corresponding to the first and second capacitor lines, respectively, are connected to the scanning line corresponding to the one scanning line, and the source electrodes of the first and second transistors are connected to the first feed line;

the gate electrode of the third transistor is connected to a scanning line apart from the scanning line corresponding to the one capacitor line by predetermined number of lines, and the source electrode of the third transistor is connected to the second feed line;

the gate electrode of the fourth transistor is connected to a scanning line apart from the scanning line corresponding to the one capacitor line by predetermined number of lines, and the source electrode of the fourth transistor is connected to the third feed line; and

the drain electrodes of the first and third transistors are connected to the first capacitor line corresponding to the line, and the drain electrodes of the second and fourth transistors are connected to the second capacitor line corresponding to the line.

2. The driving circuit of an electrooptic device according to claim 1, wherein:

in the pixels corresponding to the one scanning line, storage capacitors corresponding to data lines in odd-numbered columns are each disposed between one end of a pixel capacitor corresponding to the pixel itself and one of the first and second capacitor lines; and

storage capacitors corresponding to data lines in even-numbered columns are each disposed between one end of a pixel capacitor corresponding to the pixel itself and the other one of the first and second capacitor lines.

3. The driving circuit of an electrooptic device according to claim 1, wherein

22

the first capacitance signal is temporally constant at the predetermined voltage; and the voltages of the second and third capacitance signals are higher or lower exclusively from each other, and are switched every time one scanning line is selected.

4. The driving circuit of an electrooptic device according to claim 1, wherein

the capacitor-line driving circuit brings the first and second capacitor lines corresponding to one scanning line into high impedance after the selection of a scanning line apart from the one scanning line by predetermined number of lines and following the one scanning line is completed until the one scanning line is selected again.

5. A driving circuit of an electrooptic device, comprising:

a plurality of scanning lines; a plurality of data lines; first and second capacitor lines corresponding to each of the plurality of scanning lines, wherein the first capacitor line is separate from the second capacitor line; a common electrode;

pixels corresponding to the intersections of the plurality of scanning lines and the plurality of data lines, the pixels each including:

a pixel switching element connected at one end to a data line corresponding to the element itself, and brought into conduction when a scanning line corresponding to the element itself is selected,

a pixel capacitor disposed between the pixel switching element and the common electrode, and

a storage capacitor disposed between one end of the pixel capacitor and one of the first and second capacitor lines corresponding to the scanning line;

a scanning-line driving circuit that selects the scanning lines in a predetermined order; and

a capacitor-line driving circuit that shifts the voltage of a first capacitor line corresponding to one scanning line to a predetermined voltage when the one scanning line is selected, and when a scanning line apart from the one scanning line by predetermined number of lines is selected, changes the predetermined voltage by a predetermined value or holds the predetermined voltage; and when the one scanning line is selected, shifts the voltage of a second capacitor line corresponding to the one scanning line to the predetermined voltage, and when a scanning line apart from the one scanning line by predetermined number of lines is selected, holds the predetermined voltage or changes the predetermined voltage by the predetermined value; and

a data-line driving circuit that applies a data signal to pixels corresponding to a selected scanning line via a data line, the data signal having a voltage corresponding to the gray level of the pixels,

wherein

the capacitor-line driving circuit comprises:

first to fourth transistors corresponding to each row, wherein

the gate electrodes of the first and second transistors corresponding to the first and second capacitor lines, respectively, are connected to the scanning line corresponding to the one scanning line, and the source electrodes of the first and second transistors are connected to the first feed line;

the gate electrode of the third transistor is connected to a scanning line apart from the scanning line corresponding to the one capacitor line by predetermined number of lines, and the source electrode of the third transistor is connected to the second feed line;

23

the gate electrode of the fourth transistor is connected to a scanning line apart from the scanning line corresponding to the one capacitor line by predetermined number of lines, and the source electrode of the fourth transistor is connected to the third feed line; and

the drain electrodes of the first and third transistors are connected to the first capacitor line corresponding to the line, and the drain electrodes of the second and fourth transistors are connected to the second capacitor line corresponding to the line.

6. The driving circuit of an electrooptic device according to claim 5, wherein

the capacitor-line driving circuit brings the first and second capacitor lines corresponding to one scanning line into high impedance after the selection of a scanning line apart from the one scanning line by predetermined number of lines and following the one scanning line is completed until the one scanning line is selected again.

7. A driving circuit of an electrooptic device, comprising: 20 a plurality of scanning lines;

a plurality of data lines;

first and second capacitor lines corresponding to each of the plurality of scanning lines, wherein the first capacitor line is separate from the second capacitor line;

a common electrode;

pixels corresponding to the intersections of the plurality of scanning lines and the plurality of data lines, the pixels each including:

a pixel switching element connected at one end to a data line corresponding to the element itself, and brought into conduction when a scanning line corresponding to the element itself is selected;

a pixel capacitor disposed between the pixel switching element and the common electrode; and

a storage capacitor disposed between one end of the pixel capacitor and one of the first and second capacitor lines corresponding to the scanning line;

a scanning-line driving circuit that selects the scanning lines in a predetermined order; and

a capacitor-line driving circuit that shifts the voltage of a first capacitor line corresponding to one scanning line to a predetermined voltage when the one scanning line is selected, and when a scanning line apart from the one scanning line by predetermined number of lines is selected, changes the predetermined voltage by a predetermined value or holds the predetermined voltage; and when the one scanning line is selected, shifts the voltage of a second capacitor line corresponding to the one scanning line to the predetermined voltage, and when a scanning line apart from the one scanning line by predetermined number of lines is selected, holds the predetermined voltage or changes the predetermined voltage by the predetermined value; and

a data-line driving circuit that applies a data signal to pixels corresponding to a selected scanning line via a data line, the data signal having a voltage corresponding to the gray level of the pixels,

24

wherein a first end of the storage capacitor is connected to the pixel capacitor, and a second end of the storage capacitor is connected to only one of the first and second capacitor lines,

5 wherein when the one scanning line is selected, the capacitor-line driving circuit connects the first capacitor line corresponding to the one scanning line to a first feed line that feeds a first capacitance signal of the predetermined voltage, and when a scanning line apart from the one scanning line by predetermined number of lines is selected, the capacitor-line driving circuit connects the first capacitor line to a second feed line that feeds a second capacitance signal of one of voltages higher and lower than the predetermined voltage by a predetermined value or of the predetermined voltage,

wherein when the one scanning line is selected, the capacitor-line driving circuit connects the second capacitor line corresponding to the one scanning line to the first feed line, and when a scanning line apart from the one scanning line by predetermined number of lines is selected, the capacitor-line driving circuit connects the second capacitor line to a third feed line that feeds a third capacitance signal of the predetermined voltage or the other one of voltages higher and lower than the predetermined voltage by the predetermined value, and

wherein the capacitor-line driving circuit comprises:

first to fourth transistors corresponding to each row,

wherein

the gate electrodes of the first and second transistors corresponding to the first and second capacitor lines, respectively, are connected to the scanning line corresponding to the one scanning line, and the source electrodes of the first and second transistors are connected to the first feed line;

the gate electrode of the third transistor is connected to a scanning line apart from the scanning line corresponding to the one capacitor line by predetermined number of lines, and the source electrode of the third transistor is connected to the second feed line;

the gate electrode of the fourth transistor is connected to a scanning line apart from the scanning line corresponding to the one capacitor line by predetermined number of lines, and the source electrode of the fourth transistor is connected to the third feed line; and

the drain electrodes of the first and third transistors are connected to the first capacitor line corresponding to the line, and the drain electrodes of the second and fourth transistors are connected to the second capacitor line corresponding to the line.

8. The driving circuit of an electrooptic device according to claim 7, wherein

the capacitor-line driving circuit brings the first and second capacitor lines corresponding to one scanning line into high impedance after the selection of a scanning line apart from the one scanning line by predetermined number of lines and following the one scanning line is completed until the one scanning line is selected again.
